William F. Reach

Dear Middleton, & Deaconess Hall
Attorney

UNITED STATES PATENT OFFICE.

WILLIAM F. REACH, OF SPRINGFIELD, MASSACHUSETTS, ASSIGNOR TO A. G. SPALDING & BROS., OF NEW YORK, N. Y., A CORPORATION OF NEW JERSEY.

SKI BINDING.

Application filed August 6, 1925. Serial No. 48,610.

To all whom it may concern:

Be it known that I, WILLIAM F. REACH, a citizen of the United States, and resident of Springfield, in the county of Hampden and 5 State of Massachusetts, have invented certain new and use Improvements in Ski Bindings, of which the following is a specification.

In the use of skis, the more expert skiers 10 prefer to use a rigid type of binding, or means for connecting the foot to the ski, but for beginners it is desirable to have a hinged connection in that there is much less likelihood of a broken or strained foot during a fall.

Heretofore, so far as I am aware, it has 15 been customary to manufacture these as separate types, the hinged type for beginners and the rigid type for those proficient 20 in their use.

The present invention aims to provide a construction which will be convertible readily to either type, will be simple in construction, and strong and durable in use.

With these and other objects in view, which will hereinafter appear, the invention includes the novel features of construction and arrangement and combination of parts hereinafter described, the precise nature 25 and scope of my invention being defined and ascertained by the claims appended hereto.

What I at present consider the preferred embodiment of my invention is illustrated 30 in the accompanying drawings, in which:—

Figure 1 is a plan view of a ski partly broken away, with my improved binding or foot securing means applied thereto, with the parts in rigid position.

Fig. 2 is a side elevation of the same.

Fig. 3 is a view similar to Fig. 1, with the parts adjusted to hinged position and partly broken away.

Fig. 4 is a section on line 4—4 of Fig. 3.

Referring by reference characters to these drawings, the numeral 1 designates the ski runner which, as it may be of the ordinary or any desired construction, is shown conventionally and broken away at each end.

Secured to the upper face of the ski is a plate member 2, preferably by means of depending ears 2^a embracing opposite edges of the ski runner and secured thereto by means such as wood screws 3. This plate has a 55 central forward extension or reduced end

provided with a series of parallel eyes 2^b, 2^c, 2^d. Superimposed on the plate 2 is a toe plate 4 which has extended sides forming a pair of forwardly projecting portions 4^a to embrace the central eyes 2^b, 2^c. 60

The two parallel pintle receiving eyes 2^b, 2^c are adapted to interchangeably receive the hinge pin 5 which connects the toe plate 4 to the base plate 2.

The toe plate 4 carries brackets 4^e for receiving the customary toe straps.

The bed plate 2 has grooved lugs or ears 2^e which, when the toe plate is in its rear-most position as shown in Fig. 1, with the hinge pintle lying in the pintle eyes 2^b and 2^c, engage the rear portions of the edges of the toe plate and hold the same against upward movement and hence locked to the ski, whereby a rigid toe plate is secured. If, however, the hinge pintle 5 is removed 70 and the toe plate slid forward to align the eyes 2^c and 4^a and the pintle again inserted the rear edges of the toe plate will be disengaged from the lugs 2^e and upward hinging of the toe plate permitted. 75

It is desirable that the toe plate shall be resiliently held against the bed plate and to this end I provide a pin 6 in the eye 2^a having its ends projecting on either side thereof, and encircled by the helical coiled 80 springs 7^a preferably connected by a loop member 7 which overlies the upper face of the ski and resists turning action of the coils. These springs are provided with spring arms 7^b which extend rearwardly 85 and overlie the toe plate within the clips, and serve to hold the toe plate resiliently or yieldingly pressed down on the bed plate.

Preferably the spring arms are so arranged that they overlie the ends of the 90 hinge pin 5 and serve to hold it in place. When it is desired to remove the hinge pin it is only necessary to lift up the spring ends and swing them outside of the clips 4^a, whereupon the pin 5 may be removed, 100 the toe plate adjusted, the pin 5 reinserted, and the spring ends replaced in pin holding position.

A sole contact member 8 of suitable material, has its forward end riveted to the 105 toe plate while its rear end carries the usual "harness" or attaching straps 9 and 10, which for convenience of illustration are shown broken away.

Any suitable means may be provided for 110

holding the spring coils in position on the justed to the other position, and spring 45 projecting ends of the pin 6, and the latter in position in the eye 2^a. The cotter pin 6^a means for exerting pressure on the toe plate, in position in the eye 2^a. The cotter pin 6^a said spring means being adapted to removably hold the hinge pin in position.

5. Having thus described my invention, what I claim is:-

1. In a ski binding, a base plate having a toe plate pivotally connected therewith, and 10 means for locking said toe plate against any pivotal movement.

2. In a ski binding, a base plate having a toe plate pivotally connected thereto, spring 15 means tending to hold said plate yielding- ly pressed against the base plate, and means whereby the toe plate may be locked against pivotal movement.

3. In a ski binding, a base plate, a pair of transverse hinge eyes carried thereby, a 20 toe plate having a bifurcated portion pro- vided with aligned hinge eyes to cooperate with said first mentioned hinge eyes, where- 25 by the toe plate may be set in either of two positions, a removable hinge pin for con- necting the eyes of the toe plate with the eyes of the base plate, and means carried by 30 the base plate and engaged by the toe plate for holding the latter rigid when the toe plate is adjusted to one position, and per- mitting pivotal movement thereof when ad- justed to the other position.

4. In a ski binding, a base plate, a pair of transverse hinge eyes carried thereby, a toe plate having a bifurcated portion pro- 35 vided with alinged hinge eyes to cooperate with said first mentioned hinge eyes, where- by the toe plate maybe set in either two positions, a removable hinge pin for con- necting the eyes of the toe plate with the 40 eyes of the base plate, and means carried by the base plate and engaged by the toe plate for holding the latter rigid when the toe plate is adjusted to one position and permit- 45 ting pivotal movement thereof when ad-

5. In a ski binding, a base plate, a pair of transverse hinge eyes carried thereby, a toe 50 plate having a bifurcated portion provided with aligned hinge eyes to cooperate with said first mentioned hinge eyes whereby the toe plate may be set in either of two positions, a removable hinge pin for connecting 55 the eyes of the toe plate with the eyes of the base plate, and means carried by the base plate and engaged by the toe plate for holding the latter rigid when the toe plate is adjusted to one position, and permitting 60 pivotal movement thereof when adjusted to the other position, and spring arms extend- ing across the hinge pin and bearing against the upper surface of the toe plate.

6. In a ski binding, a bed plate carrying 65 toe brackets, and having a relatively narrow portion provided with a pair of longitudi- nally spaced parallel hinge eyes and having transverse pin projections at its forward 70 end, a toe plate having a bifurcated forward portion provided with spaced aligned hinge 75 eyes to selectively cooperate with the first mentioned hinge eyes, said base plate having locking lugs to cooperate with the rear cor- ners of the toe plate, and spring arms car- 80 ried by said pin projections and extending across the ends of the hinge pin and over- lying the toe plate within the toe irons.

7. In a ski, a runner, a toe plate pivot- 85 ally connected therewith, means for locking 80 said toe plate against any pivotal movement, and a sole contact member secured to said toe plate and projecting between and in rear of the toe irons, and carrying attaching 85 straps.

In testimony whereof, I affix my signature.

WILLIAM F. REACH.
